[57] CLAIM

The ornamental design for a telephone set, as shown and described.

DESCRIPTION

FIG. 1 is a top and right side perspective view of a telephone set showing my new design in cradled relationship;

FIG. 2 is a top and left side perspective view thereof with the handset shown inverted and spaced apart from the base;

FIG. 3 is a front elevational view thereof;

FIG. 4 is a right side elevational view thereof;

FIG. 5 is a top plan view thereof;

FIG. 6 is a rear elevational view thereof;

FIG. 7 is a left side elevational view thereof;

FIG. 8 is a bottom plan view thereof;

FIG. 9 is a top right side perspective view of a second embodiment thereof, in cradled relationship.

FIG. 10 is a top and left side perspective view thereof with the handset shown inverted and spaced apart from the base.

The left side, right side and rear elevational views of the second embodiment shown in FIGS. 9 and 10 are exactly the same as the corresponding views shown for the front embodiment as shown in FIGS. 1-8. The only difference between first and second embodiments resides in the configuration of the top portion of the stand

near the keyboard.
